F. MILLER

WINDOW CLEANING DEVICE

Filed March 28, 1923

INVENTOR.
Frank Miller
BY
George C. Heinrich
ATTORNEY.

UNITED STATES PATENT OFFICE.

FRANK MILLER, OF WEST HOBOKEN, NEW JERSEY.

WINDOW-CLEANING DEVICE.

Application filed March 28, 1923. Serial No. 628,240.

To all whom it may concern:

Be it known that I, FRANK MILLER, a citizen of Poland, residing at West Hoboken, county of Hudson, and State of New Jersey, 5 have invented certain new and useful Improvements in Window-Cleaning Devices, of which the following is a specification.

The present invention relates to improvements in window cleaning devices, and it 10 is the principal object of my invention to provide a device of a simple and inexpensive construction, which can be readily used on a window to wash and wipe the same.

15 Another object of my invention is the provision of exchangeable handles for my novel window cleaning device which permit a use of the device with windows of varying heights.

20 These and other objects of my invention will become more fully known as the description thereof proceeds, and will then be more specifically pointed out in the appended claim.

25 In the accompanying drawing:

Figure 1 is a front elevation of a window cleaning device constructed according to the present invention.

Figure 2 is a side elevation thereof.

30 Figure 3 is an end view of a brush.

Figure 4 is a front elevation of a brush, and

Figure 5 is a side view of a modified form of handle.

35 My device comprises a frame including two side bars 10 and 11 of a form best illustrated in Figure 2 connected in their middle by means of angular bars 12 and 13, having their foot parts 14, 15, and 16, 17 secured 40 to the oppositely disposed inner edges of bars 10 and 11 by means of suitable fastening means, as for instance bolts 18, 18' or the like. The central parts of bars 12 and 13 are shaped to form a socket 19 provided 45 with inner thread for the reception of the threaded end pin 20 of a handle 21.

The lower ends of bars 10 and 11 are undercut to form gripping members 22 and 23 adapted to guide between them a flat 50 piece of rubber wiper 24 inserted into the recess formed by undercutting the ends of the bars, while screws 25 passing through the lower cross bar of the frame and the rubber wiper 24 hold the rubber in place.

The upper end of bar 10 is split as indicated at 26 to form a bearing for the end of the rod 27 of a brush 28 which is stationary on rod 27 between collars 29 and 30. The other end of rod 27 is held in side bar 11 in any convenient suitable manner. 55

The collars 29 and 30 are displaceable on rod 27 by means of nuts 31 and 32 which are screwed upon threaded parts 33 and 34 of rod 27.

The end of rod 27 is held within the 65 recess 27 of a bar 10 by means of a locking pawl 35 pivoted at its lower end as at 36 on bar 10, while its upper end is recessed to form shoulders 37 and 38 between which the end of rod 27 is firmly gripped and held 70 in place.

If the use of a long handle is desirable, a handle 39 as shown in Figure 5 is preferably used, the upper angularly bent end of which is threaded as at 40 and adapted to 75 be engaged in socket 19.

The device operates as follows:

After the brush has been suitably secured on rod 27 by means of collars 29, 30 and nuts 31 and 32, rod 27 is placed with one 80 end into the hole in bar 11, while its other end is placed into the recess 26 of bar 10 and securely clamped into place by means of clamp pawl 35. According to the size of the window to be cleaned handle 21 or 85 handle 39 are attached to bars 12, 13 by the engagement of their threaded pins 20 and 40 respectively with socket 19.

When now the brush is wetted and the frame is guided over a window either longitudinally or laterally, the same will be 90 washed and can then be wiped by means of an obvious manipulation of the wiper 24.

Having thus described my invention, what I claim is:

In a window cleaning device, a frame comprising side bars connected at one end by a cross bar and free of connection at the opposite end, the cross bar being formed with a longitudinal slot for the reception 100 of a wiping element, a wiper held therein and a brace strip connecting the side bars intermediate their ends and centrally formed for the reception of a handle.

In testimony whereof I have affixed my 105 signature.

FRANK MILLER.
